FLOW APPARATUS FOR OIL WELLS

Chester A. Rasmussen, Long Beach, Calif., assignor to Rasmussen Service Company, Long Beach, Calif., a corporation of California

Application March 13, 1939, Serial No. 261,464

8 Claims. (Cl. 103—232)

My invention relates to the oil well art, and is directed particularly to a controllable arrangement for introducing fluid into the formation fluid of a well at a relatively low level to cause or encourage well flow to the surface. Generally the introduced fluid is largely if not wholly gaseous in character.

One general problem in such a flow arrangement is to achieve a practical and economical construction for conveying the introduced fluid to the desired depth, and a second problem is to provide for controlling the rate of introduction into the well fluids in accordance with changing operating conditions. In practice, these two problems are closely interrelated and must be solved together.

With reference to the problem of conveying the gas to the desired depth, the simplest arrangement, as taught by the prior art, is to extend a pipe line into the well tubing from the source of compressed gas to form two fluid channels, one channel being defined by the pipe itself and the other channel being provided by the space between the exterior of the pipe and the surrounding well tubing. One of the two channels is employed to convey the gas under pressure downwardly into the well fluid and the intermixed fluids are carried upwardly to the surface of the well through the other channel. The disadvantages of such an arrangement are, first, the cost of sufficient pipe to extend the entire distance from the surface of the well to the required depth; second, the time consumed in handling such pipe whenever it is necessary to withdraw the well tubing; and, third, the fact that the pipe usually takes up space throughout nearly the entire length of the well tubing and restricts the upwardly flowing fluid stream over the entire upward course of that stream.

It has been suggested heretofore in the art that an upper annular pressure chamber in a well may be provided by using a packer between the well tubing and the surrounding well casing to seal off an annular space extending from the packer to the well surface. If gas at the required pressure for actuating well flow is found in the upper strata of the well formation, a not uncommon situation, the well casing may be apertured to admit such high pressure gas into the annular high pressure chamber above the packer, the chamber conveniently serving as a reservoir for the high pressure gas. If the required supply of gas under pressure is not found in the upper well strata, it is necessary to introduce gas under pressure into the annular pressure cham-

ber from the surface of the well, the high pressure gas being produced at distant wells or being provided by a compressor at the surface. Whether the high pressure gas originates in well strata or is brought to the well from an external source, the annular space above the packer not only serves as a gas reservoir but also serves as a channel or passageway for conveying the compressed gas downwardly.

10 In all such arrangements heretofore employed, the lowermost level at which the gas may be introduced into the well fluids is limited by the level of the packer, since the gas is introduced into the well fluids through a port or ports in the tubing wall. It is not always practical and desirable however to install such a packer at a relatively low level as required by a well having a relatively low inherent liquid level. One object of my invention is to meet such a situation by employing the annular pressure chamber as passage means to convey the gas to a substantial depth and then to provide further passage means within the well tubing to convey the compressed gas to any further depth desired, an outstanding feature of such an arrangement being that the point at which the gas is actually released into contact with the well fluids is not limited in well depth by the position of the packer defining the lower end of the pressure chamber.

20 In a well installation providing the annular pressure chamber as means to convey the gas to a substantial depth, the problem of controlling the rate at which the compressed gas is introduced into the well fluid presents certain difficulties. In the first place, a subterranean valve must be employed because the gas stream is not subject to control until it passes from the annular pressure chamber. In the second place, whatever subterranean valve is employed must be subject to accurate adjustment from the top of the well as operating conditions change. One object of my invention in this regard is to provide a subterranean valve subject to accurate remote control and to provide a passage arrangement in 25 a well associated with the lower end of the annular pressure chamber that is adapted for incorporation of the remote control valve.

Other objects of my invention relate more specifically to the valve arrangement per se; my underlying conception being broadly a new method of subterranean valve operation from a remote control point. Various arrangements for such subterranean valve operation are described and claimed in my copending application Serial No. 55 208,106, filed May 16, 1938, entitled "Producing

apparatus for oil wells." In this aspect my invention is characterized by the conception of a subterranean valve movable through a range of open positions for various rates of flow, the valve being adapted to maintain any of a number of open positions to which it may be moved and being adapted for such movement in response to means lowered into the well. In the preferred form of my invention a valve-operating means lowered into the well engages the valve in one manner to cause valve movement in one direction and an alternative valve-operating means is adapted to be lowered into the well to engage the valve member in a second manner to move the valve in the opposite direction.

One of the important objects of my invention in the preferred forms is to provide an arrangement whereby accurate valve adjustment may be had regardless of the depth at which the valve may be located. A feature of the invention is the conception of a valve-operating means that may be accurately set or adjusted at the surface of the well for an accurately predetermined valve actuating effect to be accomplished when the tool is lowered into the well.

The above and other objects of my invention will be apparent from the following detailed description taken with the accompanying drawings.

In the drawings:

Fig. 1 is a diagrammatic representation, partly in section, of an oil well incorporating one form of my invention;

Fig. 2 is an enlarged vertical section through the valve assembly of Fig. 1;

Figs. 3, 4, 5, and 6 are transverse sections taken respectively along the lines 3—3, 4—4, 5—5, and 6—6 of Fig. 2;

Fig. 7 is an enlarged vertical section of a portion of the valve assembly showing a valve-lifting tool in engagement with a valve member;

Fig. 8 is a similar view of the tool being withdrawn from the valve assembly;

Fig. 9 shows in side elevation essential portions of a modified form of my invention, the view being partly in section;

Fig. 10 is a somewhat enlarged axial section through the valve assembly of Fig. 7;

Figs. 11 and 12 are transverse sections taken respectively along the lines 11—11 and 12—12 of Fig. 10; and

Fig. 13 is an enlarged section of a part shown in Fig. 9.

Fig. 1 shows a casing 20 in an oil well bore extending downwardly to a production zone 21, the casing being perforated in the usual manner to admit well fluids. Well fluid entering the lower end of the casing is conducted upward through the usual string of tubing 22 through a casing head fitting 23 to an external nipple 24 and thence is discharged into a lateral pipe 25.

A packer 21 around the tubing string 22 seals the annular space between the tubing string and the surrounding casing, thereby forming an annular pressure chamber 28 extending upwardly to the casing head fitting 23. If gaseous fluid of the requisite pressure for boosting flow upwardly through the tubing string is available in well formations within the vertical range of the pressure chamber 28, the casing 20 will be suitably apertured to permit such gas to enter directly into the pressure chamber. If, however, the gas must be derived from an outside source, a suitable supply pipe 29 controlled by a valve 30 will be connected with the pressure chamber at the top of the well.

If the inherent liquid level, i. e., the level to which liquids from the production zone 21 tend to rise, is at the well depth indicated by the dotted line 32, Fig. 1 will represent a common situation in which maximum efficiency in the employment of gas from the pressure chamber 28 to actuate well flow requires, first, that passage means be provided for conducting gas from the pressure chamber to a point below the level 32, and, second, that adjustable means be provided for accurately controlling the rate of gas delivery through such passage. In the present invention it is contemplated that a tubular member or pipe 33 in the tubing string 22 will extend downwardly below the level 32 to provide the required passage and it is further contemplated that the valve assembly generally designated 35 will be incorporated in the tubing string for controlling the rate of gas flow through such passage.

The valve assembly 35 may include, as best shown in Fig. 2, a connecting sleeve 36 at the lower end of the assembly, a lower section 37 of special tubing and an upper section 38 of special tubing, these three members being threaded together as a unitary portion of the tubing string. The connecting sleeve 36, in addition to connecting the lower section 37 into the tubing string, supports the previously mentioned pipe 33 that extends from the valve assembly downwardly through the tubing string. In the preferred form of my invention a support bushing 40 has an annular flange 41 resting on the top circular edge of the connecting sleeve 36 and is provided with internal threads for engagement with the line of pipe 33 and internal threads to receive and support a standpipe 42 within the valve assembly, the standpipe being in effect a continuation of the pipe line 33. It will be noted that the pipe 33 forms an inner passage 43 and defines with the surrounding tubing 22 an outer passage 44. To make the outer passage continuous through the connecting sleeve 36 and the support bushing 40, the bushing proper is smaller than the surrounding sleeve to provide ample clearance space 45, as shown, and the flange 41 of the bushing is provided with a plurality of longitudinal bores 46, as indicated in Figs. 2 and 6, communicating both with the clearance space 45 and with the annular space 47 between the standpipe 42 and the lower section 37.

The lower tubing section 37 of the two tubing sections in the valve assembly 35 is provided with a plurality of peripheral ports 50 communicating with the surrounding pressure chamber 28. By preference, the ports 50 are all on the same level and all communicate with an inner annular recess 51 in the lower section 37. Slidably mounted in the valve assembly 35 is a valve-sleeve 53 that fits snugly against both the standpipe 42 and the surrounding wall of the tubing section 37 thereby effectively sealing the upper end of the annular passage 44. The valve-sleeve 53 is provided with a plurality of longitudinally spaced ports 54 dimensioned to permit various rates of flow when registered with the annular recess 51. It will be noted that the major portion of the standpipe 42 is slightly reduced in diameter to provide an annular clearance space 55 so that gas from the pressure chamber 28 passing through the ports 50 and 54 may continue downwardly inside the valve-sleeve into the annular passage 44 surrounding the pipe line 33.

It is contemplated that the valve sleeve 53 will

be movable to various positions for various rates of flow by valve-manipulating means lowered into the well and that the valve-sleeve will be adapted to maintain various positions to which it may be adjusted by such means. For the purpose of releasably or yieldingly holding the valve-sleeve at selected positions, various expedients may be employed. For example, in the preferred form of my invention I provide a yielding latch arrangement. The drawings show a latch means 56 of circular configuration comprising a plurality of flexible latch fingers 57 integral with a flanged ring 58, the flanged ring being retained between the top end of the tubing section 37 and an annular shoulder 59 on the inner wall of the upper tubing section 38. Preferably, the valve-sleeve 53 is provided with a series of annular recesses or grooves 60 for engagement by the latch fingers 57, the ends of the latch fingers being shaped complementary to the grooves. In such an arrangement the grooves, of course, are spaced in accordance with the spacing between the sleeve ports 54 so that whenever the latch fingers 57 engage a groove, a corresponding set of sleeve ports 54 will register with the annular recess 51 in the valve assembly.

The means for moving the valve-sleeve 53 downwardly is generally designated 62 in the drawings. It may comprise an elongated weight 63 that is lowered into the tubing string by means of a suitable cable 64, the weight having a head 65 at its lower end for abutment against the upper end of the valve-sleeve 53. The weight 63 may be of such mass that it is necessary merely to lower the weight against the upper end of the valve-sleeve 53 to cause the valve-sleeve to shift downwardly as required, or a lighter weight may be used to depress the valve-sleeve by impact rather than by sheer weight.

Preferably the arrangement is such that this valve-operating tool is adjustable at the surface of the well to actuate the valve-sleeve 53 to a predetermined extent. To provide for such action the tubing section 38 is formed with an inwardly directed annular shoulder 66 that is larger in inner diameter than the inner diameter of the valve-sleeve 53, but is smaller in inner diameter than the outer diameter of the valve-sleeve. The periphery of the weight 63 is threaded to receive an adjustable stop-collar 67 complementary to the stop shoulder 66, the adjustment of the collar longitudinally on the weight determining the maximum extent to which the movable valve-sleeve is depressed by the lowered weight.

It will be noted that the weight is formed with an axial passage 68 and radial passages 69 to provide a fluid course therethrough. Such a fluid course facilitates movement of the tool through fluid in the tubing string and makes it possible to suspend the tool in the tubing when not in use. Preferably the cable 64 extends through a suitable packing gland 70 at the top of the nipple 24 so that the tool may be manipulated while relatively high pressure conditions prevail within the tubing string.

Movement of the valve-sleeve upwardly is likewise accomplished by a tool lowered in the well. For example, I may employ a grappling tool generally designated 75 shown in Figs. 7, 8, and 10. The valve-sleeve 53 may be readily adapted for cooperation with such a tool simply by providing an annular channel 80 in its inner wall.

The body 81 of the grappling tool is of tubular construction, being open at its lower end and having a series of radial apertures 82 so that fluid

may pass through the tool when it is being lowered through the fluid column in the tubing string. The upper end of the body 81 may be screw-threadedly connected to a jar shown in Fig. 9 that includes a rod 83 having an anvil head 84. A cylindrical hammer 85 surrounding the rod 83 has an inwardly extending annular shoulder 86 disposed to engage the anvil head 84 from below for supporting the tool body 81. This cylindrical hammer 85 may be supported by a cable or heavy piano wire 87, by means of which, after the tool is lowered into position, the hammer may be manipulated for repeated impact against the anvil head 84 in a manner well understood in the art.

Towards its upper end the tool body 81 carries a fixed collar 88. Spaced below this fixed collar is a second sliding collar 90, the tool body being enlarged to provide a shoulder 91 against which this latter collar is normally urged by a helical spring 92 that embraces the tool body in compression between the two collars. Slidably embracing the tool body 81 below the sliding collar 90 is a grappling sleeve 95 having integral therewith a circular series of longitudinally extending flexible fingers 96, the lower ends of the fingers providing a circular series of enlargements 97. The grappling sleeve is formed with a shoulder 98 dimensioned to engage the upper end of the valve-sleeve 53, and the fingers 96 are dimensioned to place the enlargements 97 in registry with the engagement channel 80, as may be understood by reference to Fig. 7.

The grappling sleeve 95 is supported by a collar 100 that is fixed with respect to the tool body 81 by a suitable pin 101. In one practice of my invention, this pin is of frangible material so that the pin may be severed to free the collar 100, the collar being thereby permitted to drop against an annular shoulder 102 provided by an enlargement 103 in the tool body. To permit insertion of the pin 101, diametrically disposed apertures 104 are provided in the grappling sleeve 95, and to permit subsequent removal of the severed parts of the pin, the upper end of the grappling sleeve may be cut away at diametrically opposite points, as indicated at 105. When the pin 101 holds the collar 100 at its elevated position, the grappling sleeve 95 is at a position placing the finger enlargements 97 opposite a tapered circumferential rib 106 formed in the tool body 81, this rib serving to expand the circular series of finger enlargements into an outside diameter greater than the inside diameter of the sliding valve-sleeve 53, so that the finger enlargements may engage the engagement channel 80 of the valve-sleeve in a positive manner, as shown in Fig. 7.

If, in the course of operating a well, it is desirable to shift the inner valve-sleeve upward, the grappling tool 75 is lowered into the well, the tool being guided past all obstructions in the tubing string by a conical nose 107. When the grappling tool encounters the valve-sleeve 53, it is forced into the sleeve either by sheer weight of the tool or by impacts of the hammer arrangement described. Since the circular series of finger enlargements 97 is expanded by the rib 106 into greater external diameter than the internal diameter of the sliding valve-sleeve, the forcing of the tool body 81 into the valve-sleeve causes the finger enlargements to be dislodged upward, which dislodgement causes the grappling ring to move against the sliding collar 90 and further to compress the spring 92. The finger enlarge-

ments 97 are so dimensioned with respect to the diameter of the tool body that when they are dislodged upward from the periphery of the expanding rib 106, the fingers may enter the sliding valve-sleeve. It is apparent that the spring 92 will continuously tend to restore the finger enlargements to their normal positions on the periphery of the expanding rib 106 so that as soon as the finger enlargements reach the engagement channel 80 of the valve-sleeve, the spring 92 causes relative movement between the grappling sleeve 95 and the tool body 81, restoring the finger enlargements to their normal positions thereby bringing the grappling tool into positive engagement with the valve-sleeve, as indicated in Fig. 7.

Once the grappling tool is properly seated, the cable may be spooled in to withdraw the tool. The upward movement of the grappling tool carries the sliding valve-sleeve 53 to its uppermost position which may be the closed position of the valve, at which point the sliding valve-sleeve of Fig. 7 abuts the shoulder 66 whereupon jarring the tool severs the pin 161. Severance of the pin permits the grappling sleeve to drop, thereby shifting the finger enlargements 97 downward to a position of restricted outside diameter as shown in Fig. 8. This downward movement of the finger enlargements permits the grappling tool to retract in effective diameter for escape from the valve-sleeve.

It is apparent from the foregoing description that the annular shoulder 66 formed in the tubing string serves the dual purpose of a tool-stop to cooperate with the valve-operating tool 62 and of a stop for the valve-sleeve to cause disengagement of the grappling tool 81.

The operation of my invention may be readily understood by those skilled in the art. The requisite gas pressure is maintained in the chamber 28 either because of communication with an adjacent gas-producing stratum or because of gas under pressure introduced into the chamber through the external pipe 29. In normal operation gas from the pressure chamber 28 is conducted to a relatively low level of the well a substantial distance below the packer 27, the downward movement of the gas being through the annular passage 44 surrounding the inner tubular member or pipe 33. The gas stream passes into the lower end of the pipe 33 and moves upwardly through the pipe 33 commingled with the liquids from the production zone 21. Gas under suitable pressure introduced into a well in this manner will cause the formation fluids to be lifted to the surface of the well, the upwardly flowing fluid stream traversing the inner pipe 33 to the valve assembly and from the valve assembly moving upwardly through the tubing string to the delivery pipe 25 at the top of the well. In the usual practice of my invention the valve-operating tool 62 will normally be suspended in the tubing string 22 above the valve assembly, as indicated in Fig. 1, and it will be found desirable to use the tool to increase the rate of gas introduced into the well fluids from time-to-time. In the preferred form of my invention shown in the drawings the successive valve apertures 54 in the valve-sleeve 53 that are brought into operation by progressive downward movement of the valve-sleeve are of progressively greater flow capacity. The usual adjustment of the valve-sleeve, then, will be downwardly, and such adjustment may be readily accomplished by lowering the tool 62 against

the valve-sleeve from time-to-time, the stop-collar 67 on the tool being retracted to its uppermost position or entirely removed from the tool. In such practice, however, considerable skill is required to keep from shifting the valve-sleeve downwardly too far. Uncertainty is eliminated from the valve-adjusting operation, however, by operating the tool only in cooperation with the stop-shoulder 66 in the valve assembly. Since the adjustment of the stop-collar 67 longitudinally of the weight 63 determines in a positive manner the extent of the tool movement against the valve-sleeve, regardless of the depth at which the tool is operated, the operator may readily ascertain the required position of the collar 67 on the tool to bring a given set of sleeve ports 54 into operative position, the operator being guided by reference marks on the tool, or, if necessary, being guided by knowledge of the dimensions and space relations in the valve assembly.

In the course of well operation with my invention, it may be desirable at times to shift the valve-sleeve upwardly to restrict or entirely preclude the introduction of gas into the well fluid. Such upward movement is accomplished, as heretofore described, by employing the grappling tool 75. In the construction shown, the employment of the grappling tool always leaves the valve-sleeve in its uppermost position entirely cutting off gas flow so that when it is desired merely to reduce flow of gas it is necessary first to use the grappling tool 75 and then to lower the valve-operating tool 62 into the well with the collar 67 adjusted to bring the suspended valve-sleeve ports 54 into operation.

An alternative form of my invention, the construction of which is indicated in Figs. 9 to 13, differs from the first form in that the valve assembly 25a is below the level of the packer 27a and in that the downward movement of the gas from the pressure chamber 28a is through a tubular member or pipe 33a instead of through the annular passage 44a surrounding that pipe. In other respects, however, the construction is largely the same and corresponding numbers are employed to designate corresponding parts.

The valve assembly 25a is incorporated in the tubing string 22 in a manner similar to that heretofore described, but the valve assembly is surrounded by a cylinder 110 extending from a point below the valve assembly to a point above the packer 27a. The packer is mounted on this cylinder and forms a seal between the cylinder and the casing 26, the lower end of the pressure chamber 28a being defined by the packer. The lower end of the cylinder 110 is sealed off by a suitable collar 111 that is welded or otherwise affixed to the outside of the tubing 22. The upper end of the cylinder 110 is shown threaded into a bushing 112 that embraces the tubing 22, the bushing having apertures 113 that provide communication between the pressure chamber 28a and the annular space 114 surrounding the valve assembly. It is apparent that by virtue of this construction the valve assembly may be placed at any depth in the well below the packer 27a by merely extending the cylinder 110 downwardly as required.

As best shown in Fig. 10, the valve assembly 25a includes a lower cylindrical coupling 120, a lower tubing section 121, and an upper tubing section 122. Mounted in the lower end of the valve assembly 25a is a tubular member 123

corresponding to the standpipe 43 of the first described construction, the lower end of which has a radial flange 124 that is held against the coupling 120 by a suitable annular shoulder 125 projecting inwardly from the tubing section 121. The lower end of the tubular member 123 is formed to provide a spider integral therewith having radial legs 128 as may be understood by reference to Figs. 10 and 12. Radial bores 129 through the spider legs 128 provide fluid communication between an annular space 130 surrounding the tubular member 123 and a central bore 131 in the spider. The bore 131 is threaded to receive the upper end of the pipe 33a.

The lower tubing section 121 of the valve assembly is provided with radial ports 133 and a corresponding inner annular recess 134 as heretofore described, so that gas passing from the pressure chamber 28a into the annular space 114 may pass from the annular space into the interior of the valve assembly. To control the rate at which gas enters the valve assembly in this manner, I provide a slidable valve-sleeve 135 corresponding to the first described valve-sleeve 53.

The upper portion of the valve-sleeve 135 is of a diameter to fit snugly with the surrounding tubing section 121, while the lower portion 136 of the valve-sleeve is of somewhat reduced diameter to fit snugly into the tubular member 123. By this arrangement the valve member seals off the upper end of the annular space 130 surrounding the tubular member 123. For the purpose of admitting gas to the annular space 130 from the pressure chamber 28a at various rates of flow, the valve-sleeve 135 is provided with a plurality of longitudinal bores 137 opening toward the annular space 130 and various radial bores or apertures 138 spaced longitudinally along the wall of the valve sleeve in communication with the longitudinal bores 137. Preferably the construction is such that when the valve-sleeve 135 is at its uppermost position against the shoulder 66, gas flow into the valve assembly is entirely cut off, and when the valve-sleeve is moved downwardly from its uppermost position, ports of successively large flow capacity are brought successively into effective position. The upper end of the valve-sleeve 135 preferably has the same construction as heretofore described, and is provided with peripheral grooves 60 for cooperation with the previously described latch means 56. It will be noted that the valve-sleeve is also provided with the annular channel 68 for cooperation with the previously described grappling tool 75.

This second form of my invention is manipulated and controlled from the surface of the well by tools lowered into the well from the surface, as previously described. When one or more of the ports 138 of the valve-sleeve 135 registers with the annular recess 134 to receive gas from the ports 133, the gas passes downwardly through the longitudinal bores 137 of the valve-sleeve and enters the annular space 130. From the annular space 130 the gas passes through the bores 129 and 131 into the downwardly extending pipe 33a. The pipe 33a extends to a point below the inherent liquid level of the well so that the gas released therefrom causes well fluids to stream upwardly through the annular channel 139 surrounding the pipe 33a. The upwardly flowing stream of well fluid passes around the legs 128 of the previously mentioned spider and then

through the valve-sleeve 136 into the tubing string above the valve assembly. Preferably the gas issuing from the lower end of the pipe 33a is directed upwardly into the surrounding column of well liquids to favor the upward flow thereof. For this purpose I may provide the lower end of the pipe 33a with a nozzle fitting 140 shown in Figs. 9 and 13. This particular fitting has an axial passage 141 receiving gas from the pipe 33a and has a plurality of divergent upwardly directed discharge passages 142.

I have shown and described preferred embodiments of my invention in specific detail for the purpose of disclosure, and to illustrate the principles involved. It will be apparent to those skilled in the art that various changes and modifications may be made without departing from the spirit of my invention, and I reserve the right to all such changes and modifications that properly come within the scope of my appended claims.

I claim as my invention:

1. In an oil well including a bore hole with a casing, the combination of: a string of tubing within the casing; a packer in the annular space between said tubing and casing sealing off an upper annular chamber for fluid under pressure; walls forming a fluid passage leading from said pressure chamber to the interior of said string of tubing at a relatively deep level a substantial distance below the packer; and valve means in the well movable through a plurality of open positions to permit various rates of fluid flow into the tubing through said passage.

2. In an oil well including a bore hole with a casing, the combination of: a string of tubing within the casing; a packer in the annular space between said tubing and casing sealing off an upper annular chamber for fluid under pressure; walls forming a fluid passage leading from said pressure chamber to the interior of said string of tubing at a relatively deep level a substantial distance below the packer; valve-operating means adapted to be lowered from the top of the well through said string of tubing; and valve means in the well movable through a plurality of open positions to permit various rates of fluid flow into the tubing through said passage, said valve means being adapted for movement from one of its open positions to another in response to lowering of said valve-operating means against the valve means.

3. In an oil well including a bore hole with a casing, the combination of: a string of tubing within the casing; a packer in the annular space between said tubing and casing sealing off an upper annular chamber for fluid under pressure; walls forming a fluid passage leading from said pressure chamber to the interior of said string of tubing at a relatively deep level a substantial distance below the packer; valve means in the well movable through a plurality of open positions to permit various rates of fluid flow into the tubing through said passage, said valve means being adapted to maintain open positions to which it may be moved; means adapted to be lowered into said string of tubing from the top of the well into contact with the valve means to move the valve means from one position to another; and stop means in the well adapted to cooperate with said lowered means to limit the effect of the lowered means upon the valve means.

4. In an oil well including a bore hole with a casing, the combination of: a string of tubing within the casing; a packer in the annular space

between said tubing and casing sealing off an upper annular chamber for fluid under pressure; walls forming a fluid passage leading from said pressure chamber to the interior of said string of tubing at a relatively deep level a substantial distance below the packer; valve means in the well movable through a plurality of open positions to permit various rates of fluid flow into the tubing through said passage, said valve means being adapted to maintain open positions to which it may be moved; stop means in the well; and means adapted to be lowered into said string of tubing from the top of the well into contact with the valve means to move the valve means from one position to another, said valve-moving means being adapted to contact said stop to limit movement of the valve means and being adjustable with respect to its contact with the stop.

5. In an oil well including a bore hole with a casing, the combination of: a string of tubing within the casing; a packer in the annular space between said tubing and casing sealing off an upper annular chamber for fluid under pressure, said string of tubing having an aperture to receive fluid from said pressure chamber; tubular means within said tubing extending to a relatively deep level, said tubular means providing within itself and in combination with the surrounding string of tubing two well passages to said deep level, one of which passages provides a channel from said tubing aperture to said deep level, the other of which passages provides a channel for well flow to the surface; and valve means in said string of tubing movable through a plurality of open positions to permit various rates of fluid flow from said aperture to said deep level.

6. In an oil well including a bore hole with a casing, the combination of: a string of tubing within the casing; a packer in the annular space between said tubing and casing sealing off an upper annular chamber for fluid under pressure, said string of tubing having an aperture to receive fluid from said pressure chamber; tubular means within said tubing extending to a relatively deep level, said tubular means providing within itself and in combination with the surrounding string of tubing two well passages to said deep level, one of which passages provides a channel from said tubing aperture to said deep level, the other of which passages provides a channel for well flow to the surface; valve-operating means adapted to be lowered from the top of the well through said string of tubing; and valve means in said string of tubing movable through a plurality of open positions to permit various rates of fluid flow from said aperture

to said deep level, said valve means being adapted for movement from one of its open positions to another in response to lowering of said valve-operating means into contact therewith.

5 7. In an oil well including a bore hole with a casing, the combination of: a string of tubing within the casing; a packer in the annular space between said tubing and casing sealing off an upper annular chamber for fluid under pressure, 10 said string of tubing having an aperture to receive fluid from said pressure chamber; tubular means within said tubing extending to a relatively deep level, said tubular means providing within itself and in combination with the surrounding string of tubing two well passages to said deep level, one of which passages provides a channel from said tubing aperture to said deep level, the other of which passages provides a channel for well flow to the surface; valve-operating means adapted to be lowered from the top of the well through said string of tubing; and a tubular valve means in said tubing string at said aperture movable up and down through a plurality of positions to permit various rates of fluid flow through the aperture, said valve means being adapted to be moved by the lowering of said valve-operating means thereagainst.

8. In an oil well including a bore hole with a casing, the combination of: a string of tubing within the casing; a packer in the annular space between said tubing and casing sealing off an upper annular chamber for fluid under pressure, said string of tubing having an aperture to receive fluid from said pressure chamber; tubular means within said tubing extending downward from above said aperture to a relatively deep level a substantial distance below said packer, said tubular means providing within itself and in combination with the surrounding string of tubing two well passages to said deep level, one of which passages provides a channel from said tubing aperture to said deep level, the other of which passages provides a channel for well flow to the surface; valve-operating means adapted to be lowered from the top of the well through said string of tubing; and an axially movable annular valve member sealing the upper end of the annular space between said tubing means and string of tubing, said valve means being cooperative with said aperture to control fluid flow therethrough, said valve means having a portion thereof exposed to the interior of the tubing string and adapted to be moved by said valve-operating means.
